UNITED STATES PATENT OFFICE.

GOTTLIEB H. HOELSCHER, OF BATTLE CREEK, IOWA.

COMBINATION SOAP HOLDER AND GRATER FOR WASHING-MACHINE DASHERS OR AGITATORS.

1,416,825.

Specification of Letters Patent. Patented May 23, 1922.

Application filed March 28, 1921. Serial No. 456,092.

To all whom it may concern:

Be it known that I, GOTTLIEB H. HOELSCHER, a citizen of the United States, residing at Battle Creek, in the county of Ida 5 and State of Iowa, have invented certain new and useful Improvements in Combination Soap Holders and Graters for Washing-Machine Dashers or Agitators, of which the following is a specification, reference being 10 had to the accompanying drawings.

It is the purpose of the present invention to provide a device of this kind, adapted for use in connection with washing machine dashers or agitators, for not only holding 15 the soap, but also provided with means for automatically grating the soap as the dasher operates.

Another purpose involves a receptacle, and means for detachably holding the receptacle 20 on the under face of the agitator or dasher to receive the soap, there being a latched cover for the receptacle, to retain the soap in position. The receptacle is designed to be of such proportions, as to permit the cake 25 of soap to easily move relative to the motion of the dasher or agitator.

The receptacle or holder may be held on the under face of the dasher or agitator by any suitable means and in some instances 30 the holder or receptacle may be set in a recess provided on the under face of the dasher or agitator, thereby insuring holding the receptacle in position.

Still another purpose embodies the provision of means carried by the interior face 35 of the cover, with which the soap engages, for the purpose of grating the soap automatically, due to the soap being given reciprocating agitating movement relative 40 to the movement of the dasher or agitator, which will tend to keep the water well supplied with soap. Obviously the hot water in the washing machine receptacle will tend 45 to soften the soap, and as the soap reciprocates, the soap will be grated thoroughly and the grated particles will pass through the openings in the cover.

While the design and construction at present illustrated and set forth is deemed preferable, it is obvious that as a result of a 50 reduction of the invention to a more practical form for commercial purposes, the invention may be susceptible of changes, and the right to these changes is claimed, pro-

vided they are comprehended within the 55 scope of what is claimed.

The invention comprises further features and combination of parts as will be herein-after set forth, shown in the drawings and claimed. 60

In the drawings:

Figure 1 is a sectional view through a conventional form of washing machine receptacle, showing the dasher or agitator in position, and showing the holder and grater 65 applied.

Figure 2 is an enlarged detail view of the agitator removed from the machine, showing the holder applied and illustrating the openings in the cover. 70

Figure 3 is an enlarged sectional view through the agitator or dasher on line 3—3 of Figure 2 transversely through the holder.

Figure 4 is a sectional view longitudinally of a holder, showing a modified form of 75 agitator, wherein the holder is mounted in a recess of the agitator or dasher.

Figure 5 is a detail perspective view of a portion of the wall of the cover, showing the flanges 14 and the teeth 15. 80

Figure 6 is a detail view showing the manner of cutting the openings and forming the flanges.

Figure 7 is an enlarged detail sectional view through the receptacle, more clearly 85 showing the latching catch connection between the cover and the receptacle.

Referring more especially to the drawings, 1 designates the receptacle of the washing machine, and 2 the dasher or agitator, 90 which is provided with a plurality of downwardly diverging agitating arms or pegs 3.

Fastened to the under surface of the agitator or dasher by means of the fastenings 4 is a holder 6 for a cake of soap. 95 While the holder is seated in a recess 5, as shown in Figure 4, it may be secured to the under face of the dasher, without the recess, as shown in Figure 3.

This holder may be of any suitable proportions, shape or configuration, preferably as shown, and may be constructed of any suitable material preferably sheet metal. This holder is designed to receive a cake of soap of any make, it being obvious that the holder 105 is designed to be of such size, longitudinally and transversely, as to permit the cake of soap to freely move and agitate therein, rela-

tive to the movement of the dasher or agitator. One of the longitudinal walls of the holder is provided with a spring catch 7, the shoulder 8 adjacent the tongue 9 of which is designed to engage the corresponding shoulder 10 of the flange of the cover 11. The cover is hingedly connected to the other longitudinal wall of the receptacle or holder, and has a marginal flange 12 which 10 engages the marginal wall of the receptacle or holder, to assist materially in holding the cover closed.

The cover is provided with a plurality of openings 13, which are preferably of elongated rectangular form, and are staggered, in order to permit the openings to be formed relatively close, and substantially throughout the entire surface of the cover. The openings of the cover are provided with longitudinally extending depending flanges 14, which extend toward the soap. In fact the soap rests upon the flanges, therefore it is obvious that the cutting edges of the flanges will cut into the surface of the soap, as the agitator moves. These flanges are formed on the longitudinal edges of the openings, by first slitting the cover as shown in Figure 6, with transverse slits at the opposite ends of the first slits, and then turning the metal 30 between the transverse slits laterally to the surface of the cover and toward the soap, as shown. Obviously the flanges of the openings act materially in grating the soap, since their edges are provided with roughened 35 portions or teeth 15, which will cut into the surface of the soap, as the soap reciprocates. The particles as cut from the surface of the soap will pass through the openings into the water and thoroughly dissolve.

40 It is obvious that the recess 5 is employed, when manufacturing the dasher or agitator for washing machines. In other words when manufacturing the dasher or agitator the recess 5 is constructed in the under surface,

and the holder secured therein by screws, but 45 when the holder is applied to agitators already manufactured and on the market, it is the aim to simply secure the holders to the undersurface of the agitator or dasher, without the use of the recess, as shown in Figure 50 3.

The invention having been set forth, what is claimed as being useful is:

1. In a device for the purpose indicated, 55 an agitator, a soap receiving receptacle carried thereby, a cover for said receptacle, said cover having openings through which grated particles of soap pass, and provided with flanges with which the soap engages for grating the same, the receptacle being large 60 enough to permit the soap to agitate therein, whereby the flanges may grate the surface of the soap during its movement.

2. In a device for the purpose indicated, 65 an agitator, a soap receiving receptacle, said agitator having a recess, in which the receptacle engages, means for fastening the receptacle on the agitator, a cover for the receptacle, and provided with openings arranged in staggered relation, through which grated 70 particles of soap pass, opposite edges of said openings having flanges, said receptacle being large enough to permit the soap to agitate therein, so that the edges of the flanges may engage and grate the surface of the 75 soap.

3. In a device for the purpose indicated, 80 an agitator, a soap receiving receptacle carried thereby, a cover for said receptacle and provided with openings through which grated particles of soap pass, said cover having flanges provided with serrated edges with which the soap engages as it moves in the receptacle, thereby grating the soap.

In testimony whereof I hereunto affix my 85 signature.

GOTTLIEB H. HOELSCHER.
